UNITED STATES PATENT OFFICE.

MATTHEW WESTRATE, OF GRAND RAPIDS, MICHIGAN.

ROTARY-TOOL MECHANISM.

Application filed November 26, 1926. Serial No. 150,860.

The present invention relates to rotatable tools; and its object is to provide an improved mechanism whereby such a tool may be rotated and fed axially.

5 This and any other and more specific objects hereinafter appearing are attained by, and the invention finds preferable embodiment in, the mechanism hereinafter particularly described in the body of this specification and illustrated by the accompanying drawings, in which:—

Figure 1 is a side view, shown partially in axial section of the rotatable tool mechanism operating between spaced horizontal furniture members.

10 Figure 2 is a top plan view of parts of said mechanism, sectioned on line 2—2 of Figure 1; and

15 Figure 3 is a top plan view of parts of the mechanism, sectioned on line 3—3 of Figure 1.

Where rotatable tools, such as screw-drivers, drills and the like, are to be operated in locations between members of furniture, etc. 20 spaced at short distances apart, it is difficult in many cases to gain such access to the tools as is necessary to rotate the same and to feed them toward the work. The object of the present invention is to obviate this difficulty.

25 In the accompanying drawings, the rotatable tool mechanism is shown operated in a narrow space, such as exists in many furniture constructions between the members thereof, such space being indicated between the furniture members 1 and 2 in Figure 1.

The illustrated mechanism comprises a base member designated generally 3 adapted to abut at its upper end on the furniture member 1 to cause the rotatable tool—in this case a screw-driver 4—to be fed downwardly so that the screw 5 may be driven into the lower furniture member 2. The tool 4 bears rotatably and axially-movably in a bearing 6 in this base, and has an operating handle which comprises two members adapted to be grasped by one hand of the operator. One of these members, 7, is mounted on the tool rotatably at 8 but is held in axially-nonmovable relation therewith by suitable means, as by the ratchet wheel 9 pinned to the tool at 10 and having the teeth 11, this member 7 being bifurcated to provide spaced arms 12, 13 extending on the opposite sides of the ratchet wheel, and in which the rotative bearings 8 of said member 7

are formed. This member has a pawl 14 spring-pressed outwardly at 15 into engagement with the ratchet wheel's teeth 11, to rotate the tool by the rotation of the handle. 60

To cause the tool to feed downwardly and to maintain its lower end 16 in engagement with the kerf 17 of the screw 5, the second member 19 of the operative handle is provided. This member 19 is a lever fulcrumed at 20 on the handle's member 7 and is bifurcated to provide arms 21 extending on the opposite sides of the body portion 22 of the base 1, and into its annular groove 23, so as to engage the upper wall 24 of this 70 groove and move the tool downwardly, whenever the outer or hand-engaged portions 25, 26 of the handle's members 7, 19 are grasped by the operator's fingers.

The base 3 comprises the body portion 22 and an extension portion 27 movable in the tool's axial direction so that its upper end 28 may abut against the under surface of the upper furniture member 1. Preferably, the body portion 22 is threaded at 29 and 80 the extension portion 27 is in form a headed nut threaded to turn on the threads of the body portion. The operator may grasp the portions 25, 26 of the two handle members 7, 19 with one hand and may turn the extension nut 27 with the other hand as occasion requires, as when the screw 5 is driven so far down that the portions 25, 26 of the handle members 7, 19 come together, and it is therefore necessary to extend the length of the 85 base 3 by turning its extension nut 27 upwardly into abutting relation with the under surface of the upper furniture member 1.

It is manifest that other tools, such as 90 drills, may be substituted for the screw-driving tool 4 illustrated.

The invention being intended to be pointed out in the claims, is not to be limited to or by details of construction of the particular 100 embodiment illustrated by the drawings or hereinbefore described.

I claim:

1. In a mechanism of the character described: a base; a rotatable tool; an operating handle comprising a member rotatable about the axis of the tool and in axially-nonmovable relation to the tool, and a lever member fulcrumed on the first-mentioned member and engaging the base for moving 105 the same and the first-mentioned member relatively to each other in the tool's axial 110

direction; means for rotating the tool by the rotation of the handle.

2. In a mechanism of the character described: a base; a rotatable tool axially-movably bearing therein; an operating handle comprising a member rotatable about the axis of the tool and in axially-nonmovable relation to the tool, and a lever member fulcrumed on the first-mentioned member and engaging the base for moving the same and the first-mentioned member relatively to each other in the tool's axial direction; means for rotating the tool by the rotation of the handle.

3. In a mechanism of the character described: a base; a rotatable tool rotatably and axially-movably bearing therein; an operating handle comprising a member rotatable about the axis of the tool and in axially-nonmovable relation to the tool, and a lever member fulcrumed on the first-mentioned member and engaging the base for moving the same and the first-mentioned member relatively to each other in the tool's axial direction; means for rotating the tool by the rotation of the handle.

4. In a mechanism of the character described: a base comprising a body and an extension movable in the axial direction of the hereinafter-mentioned tool to adjusted positions on the body; a rotatable tool; an operating handle comprising a member rotatable about the axis of the tool and in axially-nonmovable relation to the tool, and a lever member fulcrumed on the first-mentioned member and engaging the base for moving the same and the first-mentioned

member relatively to each other in the tool's axial direction; means for rotating the tool by the rotation of the handle.

40

5. In a mechanism of the character described: a base comprising a body threaded about an axis extending in the axial direction of the hereinafter-mentioned tool, and an extension nut on the body; a rotatable tool; an operating handle comprising a member rotatable about the axis of the tool and in axially-nonmovable relation to the tool, and a lever member fulcrumed on the first-mentioned member and engaging the base for moving the same and the first-mentioned member relatively to each other in the tool's axial direction; means for rotating the tool by the rotation of the handle.

50

6. In a mechanism of the character described: a base comprising a body threaded about an axis extending in the axial direction of the hereinafter-mentioned tool, and an extension nut on the body; a rotatable tool rotatably and axially-movably bearing in the body and having ratchet teeth; an operating handle comprising a member carried by the tool rotatable about the axis of the tool and in axially-nonmovable relation thereto and having a pawl engaging said teeth, and a lever member fulcrumed on the first-mentioned member and engaging the base for moving the same and the first-mentioned member relatively to each other in the tool's axial direction.
